UNITED STATES PATENT OFFICE

REUBEN HALEY, OF BEAVER, PENNSYLVANIA, ASSIGNOR TO STREET LUMINARE COMPANY, OF CHICAGO, ILLINOIS, A CORPORATION OF ILLINOIS

DESIGN FOR A GLOBE FOR STREET LAMPS

Application filed June 16, 1928. Serial No. 27,163. Term of patent 3½ years.

To all whom it may concern:

Be it known that I, REUBEN HALEY, a citizen of the United States, and resident of Beaver, in the county of Beaver and State of Pennsylvania, have invented a new, original, and ornamental Design for a Globe for Street Lamps, of which the following is a specification, reference being had to the accompanying drawing, forming part of the pres-

ent application, in which the figure is a perspective view of a globe showing my design.

I claim:

The ornamental design for a globe for street lamps, substantially as shown.

In witness that I claim the foregoing as my invention, I have hereunto affixed my signature, this 14th day of June, 1928.

REUBEN HALEY.
